INVENTOR
J. C. MARTIN, JR.

UNITED STATES PATENT OFFICE.

JESSE C. MARTIN, JR., OF SAN FRANCISCO, CALIFORNIA.

AIR-ADMISSION MEANS FOR BOILER-FURNACES.

1,321,537.

Specification of Letters Patent. Patented Nov. 11, 1919.

Application filed March 22, 1919. Serial No. 284,424.

To all whom it may concern:

Be it known that I, JESSE C. MARTIN, Jr., a citizen of the United States, and a resident of San Francisco, county of San Francisco, and State of California, have invented certain new and useful Improvements in Air-Admission Means for Boiler-Furnaces.

The hereinafter described invention relates to that class of refractory lined boiler furnaces wherein air is admitted for oxidizing the combustible gases evolved from the fuel therein and completing their combustion within the confines of the fire box.

One of the objects of the invention is to effect economy in fuel consumption by controlling the air admission into the fire box combustion chamber in relation to the amount of fuel or combustible gases delivered therein by the simultaneous operation of the fuel feed and air admission means.

Another object of the invention is to minimize the amount of excess air required for combustion purposes by simultaneous control of the fuel and air feed into the fire box combustion chamber.

An important object of the invention is its adaptation to refractory lined fire box combustion chambers wherein fuel oil is injected as a protection against failure and leakage of the sheets, seams and tubes of the fire box caused by excess cold air being taken therein, as well as the deterioration of the refractory lining through expansion and contraction caused by excess chill air admitted into the combustion chamber through carelessness in not closing the independently operated air damper doors now commonly used in connection therewith, such protection to the fire box and refractory lining being especially necessary in refractory lined locomotive fire box combustion chambers when locomotives are standing on sidings or in roundhouses with fires out.

In the accompanying drawings Figure 1 shows a broken side elevation of a locomotive boiler fire box combustion chamber provided with simultaneously operated fuel feed valve and air admittance means into the combustion chamber in accordance with my invention. Fig. 2 is a rear end elevation showing attachment of fuel feed valve control to locomotive boiler head and operative connection of front and rear air inlet damper thereto. Fig. 3 is a broken plan section on line 3—3, Fig. 2, showing means for simultaneously operating the fuel feed valve

and the front and rear air inlet dampers into combustion chamber.

Referring to the drawings numeral 1 is used to designate a refractory lined locomotive fire box boiler and 2 the pan forming therewith the combustion chamber 3. In the use of the invention fuel is injected into the combustion chamber through a burner, 4, being controlled by a regulating valve, 5. 60 Air openings leading into the combustion chamber, 3, are provided at the front and rear of the pan, 2, through damper door housings, 6, and 7, respectively. Fitted to front damper door housing, 6, and mounted 65 in bearings, 8, is damper door, 9, and likewise fitted to rear damper door housing, 7, in bearings, 10, is damper door, 11. Provided on front damper door, 9, is pivot bearing, 12, eccentric to bearings, 8, acting in 70 relation thereto as a crank center, and likewise provided in rear damper door, 11, is pivot bearing, 13, eccentric to bearings, 10.

Numerals 14 designates a fuel feed valve handle and 15 a quadrant in operative relation therewith, the quadrant being conveniently attached to the boiler head by bracket 16. Fastened to the handle, 15, and depended therefrom is extension rod, 17, upon which are secured at its lower end the 80 lever arms 18 and 19. Communicating with lever arm 18 in pivotal relation therewith is rod, 20, extending horizontally to the front end of pan, 2, where it connects pivotally to one end of lever arm, 21. The 85 opposite end of lever arm, 21, is secured on transverse rod, 22, one end of which rides in outboard bearing, 23, and the other end of which is fastened directly to the fuel regulating valve, 5, thus completing the 90 communicating link necessary for operating the fuel regulating valve 5, by handle, 15.

Numeral 24 designates a rod movably connected at one end to damper door pivot bearing, 13, and at its opposite end pivotally to lever arm, 19, rod, 24, furnishing the completing link for operating the rear damper door, 11, simultaneous with the fuel regulating valve, 5, through the movement of operating handle, 14.

Numeral 25 designates a lever arm fixed at one end on transverse rod, 22, and pivotally connected on its opposite end to one end of connecting rod, 26. Rod, 26, has its opposite end movably connected to damper door pivot bearing, 12, thereby furnishing the link for simultaneously operating the

front damper door, 9, with the fuel feed valve, 5, by the movement of operating handle, 14.

The relation of all lever arms and pivotal rods connected thereto may be changed as desired to suit the local conditions of operation, it being obvious that the lever arms may be of such length and so set that a relatively quick or slow opening of fuel feed valve, 5, may be accomplished simultaneously with a given opening of the damper doors, 9 and 11, and likewise the crank centers or pivot bearings, 12 and 18, of the front and rear damper doors, respectively, 15 may be changed to a shorter or longer throw in their eccentric relation to damper door bearings, 8 and 10, and consequently may be caused to open or close a relatively greater distance simultaneously with a given opening of the fuel feed valve, it 20 therefore being clear that the means for simultaneously operating the fuel feed valve and damper doors are adjustable to meet the conditions under which the boiler furnace may be drafted. Again should it be desired to meet special conditions of service either the front or back damper may be operated simultaneously with the opening or closing of the fuel feed valve, 5, by disconnecting either the front or rear connecting rods, 26 or 24 respectively. However, under normal operating conditions both front and rear damper doors are arranged so that maximum opening of fuel feed valve 35 gives maximum opening of air inlet through

the damper doors into the combustion chamber and closing of the fuel feed valve closes the air inlet into the combustion chamber.

The operation of the invention is illustrated in the drawings by solid lines showing the simultaneous closing of fuel feed valve, 5, operating handle, 14, and front and rear damper doors, 9 and 11, and by dotted lines showing the simultaneous opening of the fuel feed valve as indicated by operating handle at 14^a with the front and rear damper doors open in the position 9^a and 11^a.

It is obvious that many modifications of the invention may be made to suit local conditions where applied without departing from the essential principles involved.

What I claim is:

In a fuel oil burning locomotive fire box wherein a damper at the front of the fire box and a damper at the rear of the fire box are used to admit oxygen for combustion, a manually operated fuel oil feed valve, operative connection between the fuel oil feed valve and dampers, whereby upon regulating the flow of fuel oil through the valve the dampers connected thereto are simultaneously regulated and a proportional admittance of fuel oil and air into the fire box is effected.
